UNITED STATES PATENT OFFICE.

LEON RUBAY, OF CLEVELAND, OHIO, ASSIGNOR TO THE WHITE COMPANY, OF CLEVELAND, OHIO.

DESIGN FOR AN AUTOMOBILE-BODY.

47,804.

Specification for Design.

Patented Sept. 7, 1915.

Application filed May 13, 1915. Serial No. 27,937. Term of patent 7 years.

To all whom it may concern:

Be it known that I, LEON RUBAY, a citizen of the Republic of France, residing at 1559 East One Hundred and Fifteenth street, in Cleveland, Cuyahoga county, Ohio, United States of America, have invented a new, original, and ornamental Design for Automobile-Bodies, of which the following is a specification, reference being had to the accompanying drawings, forming a part thereof.

In said drawings, Figure 1 is a side elevation of an automobile body showing my design, and Fig. 2 is a plan view thereof.

I claim:

The ornamental design for an automobile body, as shown.

LEON RUBAY.
